INVENTOR

George E. Blake,

BY
Chester Bradford,

ATTORNEY.

UNITED STATES PATENT OFFICE.

GEORGE E. BLAKE, OF GREENCASTLE, INDIANA.

VEHICLE-WHEEL RIM.

SPECIFICATION forming part of Letters Patent No. 559,118, dated April 28, 1896.

Application filed November 2, 1895. Serial No. 567,776. (No model.)

To all whom it may concern:

Be it known that I, GEORGE E. BLAKE, a citizen of the United States, residing at Green-
5 castle, in the county of Putnam and State of
Indiana, have invented certain new and use-
ful Improvements in Vehicle-Wheel Rims, of
which the following is a specification.

The object of my said invention is to pro-
10 duce a strong and durable rim or felly for ve-
hicles, such as bicycles, without bending the
wood and in which the several parts shall be
strongly united to each other. Such a rim
will be first fully described, and the novel fea-
15 tures thereof then pointed out in the claim.

Referring to the accompanying drawings,
which are made a part hereof, and on which
similar letters of reference indicate similar
parts, Figure 1 is a side elevation of a bicy-
20 cle-wheel provided with a rim embodying my
said invention; Fig. 2, a side elevation of a
fragment of such a rim on an enlarged scale;
Fig. 3, a top or plan view of the same; Fig. 4,
a transverse sectional view on the dotted line
25 4 4 in Fig. 2; Fig. 5, an elevation of parts or
segments before the same are cut or turned
into their final form, and Fig. 6 a top or plan
view of a fragment of a rim in which keys or
dowels are used to connect the ends of the
30 segments instead of dovetails.

The wheel illustrated, except as to the con-
struction of the rim, is or may be of any ordi-
nary and well-known form, and will not, there-
fore, be further described herein, except in-
35 cidentally in describing the construction of
the rim. Said rim is composed of as many
sections as may be desired, (eight are shown
on a side, or sixteen altogether,) all of said
sections or segments being cut out of straight-
40 grained wood without being bent at all, and
the grain in each of said sections running
straight through from end to end thereof.
The ends of these segments or sections are
united in any desired manner, preferably by
45 means of dovetailed formation of the ends, as
shown in all the figures except Fig. 6; but, as
shown in said Fig. 6, they may be united by
keys or splices or in any other desired man-

ner. The rim - halves when assembled by
means of uniting the ends by the dovetails or
otherwise are united to each other by means of 50
interlocking tongues and grooves upon their
adjacent faces, as shown most plainly in Fig. 4.
Such an assemblage of parts in a wheel-rim
avoids the bending incident to rims of this
character of the ordinary construction and 55
leaves the wood in its natural condition with
the direction of grain and the strength en-
tirely undisturbed, while at the same time by
the peculiar assemblage of parts, as shown in
the drawings, the grains of the various por- 60
tions of wood cross each other, thus securing
them against splitting. As I have determined
by the practical operation thereof, such rims
are strong, substantial, and durable. The
portions of the original sections or segments 65
which remain after the rim is turned up and
finished are indicated by the curved dotted
lines in Fig. 5. When the portions above and
below these curved lines are cut away, it
leaves the structure substantially as shown 70
in Fig. 2. The tongues and grooves in the ad-
jacent faces of the two halves are formed by
turning after the segments or sections of each
half are assembled together.

Having thus fully described my said inven- 75
tion, what I claim as new, and desire to secure
by Letters Patent, is—

A wooden rim or felly for vehicle-wheels
composed of two halves, each half formed of
comparatively short sections laid together end 80
to end, and provided with dovetailed forma-
tion at their ends, whereby they are united,
and said sections being provided on their ad-
jacent faces with interlocking tongues and
grooves, substantially as and for the purposes 85
set forth.

In witness whereof I have hereunto set my
hand and seal, at Indianapolis, Indiana, this
30th day of October, A. D. 1895.

GEORGE E. BLAKE. [L. S.]
